BATTERY TERMINAL CONNECTOR CAP

James F. Norling, 2740 S. Jackson, Denver, Colo.

Filed Oct. 23, 1959, Ser. No. 58,046

Term of patent 14 years

(Cl. D26—1)

Fig. 1 is a side elevational view of a battery terminal connector cap, showing my new design, the opposite side being substantially a mirror image thereof;

Fig. 2 is a top plan view;

Fig. 3 is an end elevational view;

Fig. 4 is a bottom plan view;

Fig. 5 is an opposite end elevational view; and

Fig. 6 is a cross-sectional view thereof, taken on line 6—6 in Fig. 2.

The broken line fragmentary showing of a connecting conductor and compression nut in Fig. 1 is for illustrative purposes only.

I claim:

The ornamental design for a battery terminal connector cap, as shown and described.
